UNITED STATES PATENT OFFICE

2,620,969

COMPRESSOR PLANT PULSATION
DAMPENING SYSTEM

Foster M. Stephens, Monterey Park, Calif., assignor to The Fluor Corporation, Ltd., Los Angeles, Calif., a corporation of California

Application August 14, 1950, Serial No. 179,327

6 Claims. (Cl. 230—236)

1

This invention has to do with improvements in gas compressor plant pulsation dampening systems of the general type comprising a gas intake or discharge header or manifold connected to individual compressors by extended smaller diameter pipes or laterals, the sizes or volumes of the header sections to which the laterals are connected, and the length and diameters of the laterals, all being so related to such conditions as the velocity of sound in the gas and a selected gas pulsation frequency (created by the compressor), as to convert the gas stream leaving the header to a state of substantially non-pulsating flow with respect to the frequency or frequencies selected for removal.

This type of system also is dealt with in the Stephens Patent No. 2,474,555, to which reference may be had for explanation of the theoretical considerations involved in the sizing of various parts of the system therein disclosed as well as the present equipment. In general, the aforesaid patent discloses a dampening system in which the compressors communicate individually with a single header through laterals connected to longitudinal header lengths or chambers between which the header is restricted to prevent accumulation of pulse energies from one to the other of the chambers. Fabrication of the header thus involves the use of different size parts or sections in forming alternate enlarged chambers and relatively restricted intercommunications between them.

My present general object is to provide an improved lateral and header system retaining the basic fundamental acoustical characteristics of the patented system in communicating each compressor through a relatively small diameter lateral with an enlarged chamber section of the header, but providing for the elimination of cumulative resonance effects between the chambers while maintaining the header diameter substantially constant throughout, i. e. between as well as at the chambers. Generally, the invention is predicated upon the interposition between the manifold chamber sections of pipe bends, preferably corresponding in size to the chamber diameter, and presenting barriers against straight line resonance transmission between the chambers. Thus on the principal of baffling existent resonances in the chambers by the use of pipe bend connections, I am able to maintain constant the pipe diameter, a feature of value in facilitating fabrication and installation of the header on the job.

Preferably the header is made in the form of

5 straight and relatively offset sections corresponding in number to the required number of acoustical chambers, and joined by reverse bend connections service as unrestricted acoustical barriers to the extent of preventing consequential interchamber resonance amplifications.

The various details of the invention will be 10 fully understood from the following description of the illustrative embodiment shown in the accompanying drawing.

15 Referring to the drawing, the present dampening system is adaptable for connection with any number of gas compressors, diagrammatically indicated at 10, and of which three are shown merely as illustrative. Also the dampening system is connectible with either the intake or discharge sides of the compressors and will operate to remove pulsations created in the intake or discharge gas streams, as the case may be. 20 Typically, the dampening system, generally indicated at 11, is shown to be connected with the discharge sides of twin cylinder piston type compressors operating at rather low frequency to discharge the gas into the chambers 12 with which the compressors conventionally are 25 equipped.

From chambers 12 the gas is discharged 30 through laterals or pipes 13, preferably equipped with valves 14 so that any individual compressors may be cut out of the system. As illustrated, pipes 13 are of extended length and function in the nature of acoustical inductances restricting the gas streams being discharged from the chambers 12.

35 Pipes 13 are connected to a common header, generally indicated at 15, and specifically to the header sections 15a functioning, like chambers 12, as acoustical capacitances and being defined by pipe sections of substantially larger diameter 40 than the laterals 13. The header sections 15a preferably stand in parallel, laterally offset relation, and are interconnected by the reverse pipe bends 16 of corresponding diameter. As the drawing shows, the pipe bends 16 may be shaped 45 in the simple form of connected elbows extending in reverse relation and in continuity with the off-set header sections 15a. By reason of the offset relation of the header sections and their interconnection by the pipe bends 16, there can be no great line resonance transmission between the chambers. Accordingly, the arrangement tends to confine a condition of resonance existing in any one of the sections 15a by reason of pulse transmission from the compressor, to that section, and to prevent such resonance trans-

mission from one to the other of the chambers as might otherwise result in troublesome resonance amplifications. For most efficient pulsation elimination and the avoidance of standing wave conditions in the header, the length of each section 15a is kept below one-quarter of the wave length of the compressor-created pulsation to be removed.

As to considerations which may be taken into account in the design of the acoustical systems represented by the chambers 12, 15a and the interconnecting pipe 13, reference may be had to my previously issued Patents Nos. 2,405,100 issued July 30, 1946 on Pulsation Elimination in Gas Lines, and 2,474,555, issued June 28, 1949 on Gas Line Pulsation Dampening System.

I claim:

1. A gas pulsation dampening system for use with a plurality of gas compressors, comprising a relatively large diameter manifold line having longitudinal sections, pipe bends corresponding in diameter to the manifold sections interconnecting said sections and interfering with straight line flow of the gas between the sections, and pipes of smaller diameter than said manifold connected to said sections and adapted to be connected respectively with the compressors.

2. A gas pulsation dampening system for use with a plurality of gas compressors, comprising a relatively large diameter manifold line having successive laterally offset elongated pipe sections, pipe bends interconnecting said sections and interfering with straight line flow of the gas between the sections, and pipes of smaller diameter than said manifold connected to said sections and adapted to be connected respectively with the compressors.

3. A gas pulsation dampening system for use with a plurality of gas compressors, comprising a relatively large diameter manifold line having successive laterally offset elongated pipe sections, pipe bends corresponding in diameter to the manifold interconnecting said sections and interfering with straight line flow of the gas between the sections, and pipes of smaller diameter than said manifold connected to said sections and adapted to be connected respectively with the compressors.

4. A gas pulsation dampening system for use with a plurality of gas compressors, comprising a relatively large diameter manifold line having successive laterally offset and parallel elongated

pipe sections, pipe bends shaped essentially as connected elbows extending in reverse relation interconnecting said sections and interfering with straight line flow of the gas between the sections, and pipes of smaller diameter than said manifold connected to said sections and adapted to be connected respectively with the compressors.

5. A gas pulsation dampening system for use with a plurality of gas compressors, comprising a relatively large diameter manifold line having successive laterally offset and parallel elongated pipe sections, pipe bends shaped essentially as connected elbows extending in reverse relation corresponding in diameter to the manifold interconnecting said sections and interfering with straight line flow of the gas between the sections, and pipes of smaller diameter than said manifold connected to said sections near their longitudinal centers and adapted to be connected respectively with the compressors.

10 6. A gas pulsation dampening system for use with a plurality of gas compressors, comprising a relatively large diameter manifold line having successive laterally offset and parallel longitudinal sections, pipe bends shaped essentially as connected elbows extending in reverse relation corresponding in diameter to the manifold interconnecting said sections and interfering with straight line flow of the gas between the sections, and pipes of smaller diameter than said manifold connected to said sections near their longitudinal centers and adapted to be connected respectively with the compressors, the length of each of said sections being less than one-quarter of the wave length of the pulsations to be removed.
